UNITED STATES PATENT OFFICE.

LOUIS E. WAGNER, OF RICHLANDTOWN, AND FREDERIC W. PRESSER, OF PHILADELPHIA, PENNSYLVANIA.

HANGER FOR PORTIÈRES, CURTAINS, AND THE LIKE.

1,163,488.

Specification of Letters Patent.

Patented Dec. 7, 1915.

Application filed April 27, 1915. Serial No. 24,372.

To all whom it may concern:

Be it known that we, LOUIS E. WAGNER and FREDERIC W. PRESSER, citizens of the United States, residing at Richlandtown and 5 Philadelphia, respectively, in the counties of Bucks and Philadelphia, respectively, and State of Pennsylvania, have invented new and useful Improvements in Hangers for Portières, Curtains, and the like, of which 10 the following is a specification.

This invention relates to improvements in hangers for portières, lace curtains and the like and has particular application to an adjustable hanger.

15 In carrying out the present invention, it is our purpose to provide a hanger of the class described which will be found especially useful in hanging portières and the like and whereby the portières may be readily and conveniently spread apart to open position and drawn together to closed position.

20 It is also our purpose to provide a device of the class described which will embody in its construction, among other features, strips placed in face to face contact and capable of relative sliding movement to vary the length of the hanger and formed with longitudinal slots, respectively, disposed adjacent to the relatively opposite edges of the strips at the outer ends thereof, and supporting rods carried by the respective strips and carrying the pins for the portières or curtains and capable of sliding 25 movement along the rods so that the curtains may be actuated to open and closed positions, the pins carrying the curtains being connected to a cord whereby the curtains may be opened and closed simultaneously, clamping screws being passed 30 through each slot and carried by the adjacent portion of the other strip to hold the strips in the desired adjusted position.

35 With the above and other objects in view, the invention consists in the construction, combination and arrangement of parts hereinafter set forth in and falling within the scope of the claim.

40 In the accompanying drawing; Figure 1 is a view in front elevation of a hanger constructed in accordance with the present invention, the same being shown in use. Fig. 2 is a perspective view of the strips and rods carried thereby. Fig. 3 is a sectional

view on the line 3—3 of Fig. 1. Fig. 4 is 55 a perspective view of one of the pins and the links associated therewith. Fig. 5 is a similar view of one of the supports for the hanger. Fig. 6 is a fragmentary longitudinal sectional view through the hanger. 60

Referring now to the drawing in detail, 1 and 2 designate, respectively, strips placed in face to face contact and capable of relative sliding movement so that the length of the hanger may be varied, and formed with 65 longitudinal slots 3 and 4, respectively, disposed adjacent to the relatively opposite side edges of the strips in proximity to the outer ends thereof. A rod 5 has one end secured to the outer surface of the strip 1 adjacent 70 to the outer extremity thereof by means of an eye 6 and the remaining end offset as at 6' and secured to the strip 1 adjacent to the inner end thereof by means of a bolt 7 passed through the strip 1 and through the slot 4 75 in the strip 2 and having the threaded end thereof equipped with a winged nut 8. This rod 5 is disposed above the slot 3 and lies parallel therewith. A second rod 9 has one 80 end secured to the surface of the strip 2, corresponding to the surface of the strip 1 carrying the rod 5, adjacent to the outer end of the strip 2 by means of an eye 10, and the remaining end of the rod 9 is offset as at 11 and formed with an eye alining with the slot 85 3 in the strip 1 and passed through this eye in the offset end portion 11 of the rod 9 is a bolt corresponding to the bolt 7 and extending through the slot 3 and an opening 90 formed in the strip 2 adjacent to the inner end thereof, such bolt being equipped with a winged nut similar to the nut 8. By means of this construction, it will be seen that when the nuts 8 are loosened, the strips 1 and 2 may be moved relatively to one another so 95 that the length of the hanger may be changed and when the desired length has been reached the winged nuts are tightened, thereby holding the strips in the desired adjusted position. It will be noted that the strips of the 100 hanger being adjustable, enable the hanger to be adapted to door frames and window frames of various widths.

In order to support the hanger in position in the door frame or window frame, any 105 suitable means may be employed. In the present instance, a screw shank 12 is threaded into each side of the stile of the frame

and the outer end of such screw shank is equipped with a head 13 adapted to receive the adjacent end of the hanger.

In order to suspend the curtains from the rods 5 and 9 respectively, such rods are equipped with pins 14 and the pins 14 suspended from the rod 5 are connected to the latter by means of a plurality of links 15, while each pin suspended from the rod 9 is connected thereto through the medium of a single link 16, the links 15 carrying the pins 14 compensating for the distance between the rods and enabling the portières or curtains to hang evenly.

Secured to the strip 2 adjacent to the outer end thereof are eyes 17, while secured to the outer surface of the strip 1 adjacent to the outer end thereof is an eye 18 and trained through these eyes is a cord 18' having the extremities thereof disposed in proximity to each other below the eyes 17 and equipped with hand pulls 19. The upper run of the cord 18' between the eyes 17 and 18 is wrapped about the links 15 carrying the inner pin 14, while the lower run of the cord between the eyes 17 and 18 is wrapped about the single link 16 carrying the inner pin 14. Thus, when a pull is exerted upon one of the hand pulls 19 the cord will be drawn through the eyes 17 and 18 to spread the curtains apart to open position, while when the other hand pull is operated, the cord will be drawn through the eyes in the reverse direction to close the same.

While we have herein shown and described one preferred form of our invention by way of illustration, we wish it to be understood that we do not limit or confine ourselves to

the precise details of construction herein described and delineated, as modification and variation may be made within the scope of the claims without departing from the spirit of the invention.

We claim:

A hanger of the class described comprising strips placed in face to face contact and capable of relative sliding movement to vary the length of the hanger and formed with longitudinal slots, respectively, disposed adjacent to the relatively opposite edges at the outer ends thereof, a clamping screw passed through each slot and carried by the adjacent portion of the outer strips to hold said strips in adjusted position, supporting rods carried by said strips respectively, pins carried by said rods respectively and adapted to hold the portières or curtains, eyes carried by said hanger adjacent to one end thereof and spaced apart, an eye carried by said hanger adjacent to the other end thereof, and a cord trained through said eyes and having the ends thereof disposed in proximity to each other and equipped with hand pulls, and the upper run thereof between said eyes connected with the inner pin of one of said portières or curtains, and the lower run between said eyes connected with the inner pin of the other portière or curtain.

In testimony whereof we affix our signatures in presence of two witnesses.

LOUIS E. WAGNER.
FREDERIC W. PRESSER.
